PRESSURE TANK DOOR

Robert A. Davis and John F. Mummert, Birmingham, Ala., assignors to Chicago Bridge & Iron Company, a corporation of Illinois

Application May 17, 1934, Serial No. 726,170

5 Claims. (Cl. 220—55)

This invention relates to pressure tank doors, and more particularly to doors for welded pressure vessels used in the preservation treatment of wood, certain rubber processes, and for other 5 similar purposes.

One feature of this invention is that it provides a door capable of withstanding the high pressures developed in a tank of this type; another feature of this invention is that it permits 10 the head plate of the door to be a spherical section, rather than an ellipsoidal or quasi-ellipsoidal head with a short radius of curvature at the junction point with the shell; still another feature of this invention is that it employs rings 15 at the junction of the door and the shell; yet another feature of this invention is that it permits a door to be so designed that there is no rotational moment about the cross-sectional center of gravity of the door-ring when pressure 20 is applied; still other features and advantages of this invention will appear more fully from the following specification and the drawings, in which—

Figure 1 is a vertical elevation, partly in section, of the door; Figure 2 is a detailed sectional view along line 2—2 of Figure 1; Figure 3 is a horizontal sectional view along the line 3—3 of Figure 1; and Figure 4 is a top detail elevation of a section of the head.

In the particular embodiment of this invention illustrated herewith, the door head-plate is indicated by the reference numeral 10. This head-plate is welded at the point 11 to the door-ring 12. The door-ring 12 is provided with lugs 13 adapted 35 to receive between them the shank of a bolt 14, and also adapted to provide a surface against which the nut 15 and washer 16 may be tightened. The tank shell 17 has welded thereto at the point 18 a head ring 19. This head ring is provided at 40 its outer extremity with a groove 20 in which is placed a gasket 21 against which the door-ring 12 presses when the door is closed. The head-ring 19 has bolt members 23 adapted to receive the heads 24 of the bolts 14.

The door ring 12 has attached thereto hinge-members 25 which pivot about hinge-pins 26, which pins are fastened to the head ring 19 by members 27. In order to open the door it is only necessary to loosen the nuts 15, swing back the 50 bolts 14 out of engagement with the lugs 13, and the door may then be swung open, its weight being carried by the hinges 25.

Inasmuch as these tanks are designed for relatively high pressure, the two rings would under- 55 go considerable strain from the various forces

developed. The head ring is made considerably larger in cross-sectional area than the door-ring, and is thus capable of withstanding the various forces applied to it with little or no alteration in shape. The door ring, on the other hand, is 5 subject to horizontal forces comprising the tension of the bolt 14 as applied to the lugs 13, the reactance of the gasket 21 as the bolt is drawn up, and the horizontal component of the tension in the head-plate 10. It is also subject to rotational 10 moments about its center of gravity caused by the tension in the bolt, the vertical component of the tension in the head-plate, and the pressure of the liquid medium within the tank as 15 developed on the area between the joint 11 and 18 the point where the door ring contacts the gasket 21.

It has been found that the location of the joint 11 is a very important feature in the neutralizing 20 of the various moments developed. The tension 25 in the head-plate acts along a line which is a tangent to the spherical radius of curvature of the head-plate at the point of contact with the door ring 12, which tension is a function of the pressure and of that radius. The pressure per 30 inch of radius of the door-ring 12 against the gasket 21 should be about 7 times the pressure per square inch developed in the tank in order to provide a good seal. The direction of the axis of the bolt is very nearly parallel with that of the 35 horizontal axis of the door ring, and for all practical purposes may be considered as parallel. It is thus seen that the tension in the bolt must equal the sum of the two outward forces consisting of the reaction of the gasket 21 and of the 40 horizontal component of the tension in the head-plate 10.

Considering the moments tending to rotate the ring about its cross-sectional center of gravity, it is seen that for best results the tension in the 45 bolt times the distance between the axis of the bolt and the center of gravity of the door ring, minus the vertical component of the tension in the head-plate 10 times the horizontal distance of the joint 11 from the center of gravity of the door ring 12, minus the pressure exerted by the liquid medium against the inner face 28 of the door ring 50 times the horizontal distance between the center of pressure of said area and the center of gravity of the door ring, must equal zero for best results. By setting up and solving the usual mechanical design equations, it is found that the proper distance between the joint 11 and the center of gravity of the door ring 12 is a function 55 of the spherical radius of the head-plate,

the circular radius of the ring, the length of the door ring section 12 and the height of the lugs 13, and is independent of the pressure for any good design. Roughly, the horizontal distance 5 Y between the joint 11, or to be more exact the center of tension of the head at the point where it intersects the vertical plane through the center of gravity, and the center of gravity of the door ring 12 may be found by the following 10 formula:

$$Y = \frac{e(14+r)}{\sqrt{R^2-r^2}}$$

where e is the vertical distance between the axis 15 of the bolt and the center of gravity of the door ring, R is the spherical radius of the head-plate, and r is the radius of the door ring, all three being in inches. The constant, 14 in this case, will always be double the coefficient of gasket pressure 20 to gas pressure.

The above equation is derived from an equation 25 of moments about the center of gravity of the door ring, expressed in the following equation, assuming that θ is the angle between the head-plate at its junction with the door ring and a 30 diameter at that point; that B is the tension in bolts, in pounds per inch of ring circumference, when pressure P in pounds per square inch exists in the tank; that h is the distance from the center of gravity of the door ring to the end thereof in contact with the gasket; that y is the distance from the center of gravity to the joint 11 and that the angle between the axis of the bolt and that of the door ring is sufficiently small that 35 its cosine may be taken as unity:

$$Be - \frac{1}{2}PRy \cos \theta - P(h+y)\left(\frac{h-y}{2}\right) = 0$$

But

$$\cos \theta = \frac{\sqrt{R^2-r^2}}{R}, \sin \theta = \frac{r}{R}$$

and, if it is desired that the gasket pressure be 40 seven times the pressure existing in the tank, $B=7P+\frac{1}{2}PR$ $\sin \theta=P(7+\frac{1}{2}r)$. In practical work, moreover, the third term of the above 45 equation may be neglected, so that:

$$Be - \frac{1}{2}PRy \cos \theta = 0$$

Substituting for B and for $\cos \theta$, and solving 50 for y , we have:

$$y = \frac{e(14+r)}{\sqrt{R^2-r^2}}$$

This equation may be written in more general 55 form by replacing the figure 7 by the letter K , representing the desired coefficient of gasket pressure to the pressure existing within the tank, whence:

$$y = \frac{e(2K+r)}{\sqrt{R^2-r^2}}$$

The stress intensity force $\frac{1}{2}PR$, as used in the equation of moments in the paragraph above, is derived as follows, in accordance with thin 65 sphere theory: Assuming a 1 inch circle at any point on the shell of a thin sphere, the stress intensity in a tangential direction around the 1 inch circle in pounds per inch of periphery may be taken as S . The total tangential stress on the periphery of this 1 inch circle will then be πS . 70

Assuming a comparatively large sphere radius R , so that the cosine of a central angle half the size of this 1 inch circle on the shell will be substantially unity, the radially inward component 75 of the total tangential stress on the periphery of

the 1 inch circle will equal the total tangential stress $\times$ the radial projection, at the center of the 1 inch circle, of a line tangent to the radius at the edge of the circle and representing the total tangential stress. Still considering this 1 inch circle, and assuming the cosine of the central angle to be unity, the radially inward component will be

$$\frac{1/2}{R} \times \text{the total tangential stress},$$

10

or

$$\frac{1/2}{R} \times \pi S.$$

15

The radially inward component is thus

$$\frac{\pi S}{2R}$$

Where P is the internal pressure existing within 20 the tanks in pounds per square inch, the total pressure outward against the 1 inch circle considered above will be the area of the circle $\times$ the pressure, or

$$\frac{\pi}{4} \times P.$$

25

Since the radially inward component of the total tangential stress on the circle and the total pressure outward against the circle must be equal, 30 they may be equated. Therefore

$$\frac{\pi S}{2R} = \frac{\pi P}{4}$$

Solving this for S , we have $S = \frac{1}{2}PR$.

35

While we have shown and described certain embodiments of our invention, it is to be understood that it is capable of many modifications. Changes therefore in the construction and arrangement may be made without departing from the spirit and scope of the invention as disclosed in the appended claims, in which it is our intention to claim the novelty inherent in our invention as broadly as permissible in view of the prior 45 art.

40

What we claim as new and desire to secure by Letters Patent is:

1. A pressure tank, including; a shell having a head-ring welded thereto; a groove in the outward face of said head-ring; a gasket in said groove; a door-ring adapted to be drawn into engagement with said gasket; an outwardly spherically curved head-plate of relatively thin metal said head-plate having a thinness relative to its diameter such that it deforms under the action of pressures normally maintained within the tank when in use, said head-plate being substantially less than a hemisphere and welded to the inner face of said door-ring, so that any tendency of the door-ring to tilt due to the action upon it of the spherical head-plate when under pressure is minimized and leakage at the gasket is thereby prevented at a point intermediate between the cross-sectional center of gravity of said door-ring and the outer extremity of said ring, whereby the tension developed when the head is under pressure substantially neutralizes the rotational moments caused by the tension in the bolt and the pressure against the inner face 70 of the ring; lugs on said door-ring; bolt-members on said head-ring; and bolts whereby said door-ring is drawn into engagement with said gasket and head-ring.

2. A pressure tank, including; a cylindrical 75

shell having a head-ring welded thereto; a door-ring adapted to engage said head-ring; a gasket between said head-ring and said door ring; lugs on said door-ring; bolt members on said head-ring; bolts whereby said door-ring, gasket, and head-ring may be drawn into engagement; and an outwardly spherically curved head-plate of relatively thin metal, said head-plate having a thinness relative to its diameter such that it deforms under the action of pressures normally maintained within the tank when in use, said head-plate being welded to the inner face of said door-ring at a vertically outward distance from the cross-sectional center of gravity of said door-ring substantially satisfying the equation

$$Y = \frac{e(14+r)}{\sqrt{R^2-r^2}}$$

20. where e is the distance from the center of gravity to the axis of the bolt, R is the spherical radius of the head-plate, and r is the radius of the door ring, all distances being in inches, so that any tendency of the door-ring to tilt due to the action 25 upon it of the spherical head-plate when under pressure is minimized and leakage at the gasket is thereby prevented.

3. A pressure tank, including: a cylindrical shell having a head-ring welded thereto; a door-ring adapted to engage said head-ring; a gasket between said head-ring and said door-ring; lugs on said door-ring; bolt members on said head-ring; bolts whereby said door-ring, gasket, and head-ring may be drawn into engagement, and 35 an outwardly spherically curved head-plate of relatively thin metal, said head-plate having a thinness relative to its diameter such that it deforms under the action of pressures normally maintained within the tank when in use, said 40 head-plate being welded to the inner face of said door-ring at a vertically outward distance from

the cross-sectional center of gravity of said door-ring substantially satisfying the equation

$$y = \frac{e(2K+r)}{\sqrt{R^2-r^2}}$$

5 where e is the distance from the center of gravity of the door-ring to the axis of the bolt, R is the spherical radius of the head-plate, r is the radius of the door-ring, and K is the coefficient obtained by dividing the desired pressure of the door-ring against the head-ring by the pressure existing in the tank, so that any tendency of the door-ring to tilt due to the action upon it of the spherical head-plate when under pressure is minimized and leakage at the gasket is thereby prevented. 10 15

4. Apparatus of the character described, including; a cylindrical shell having a head ring; a door ring adapted to engage said head ring; a gasket between said head ring and said door ring; 20 means for drawing said door ring, gasket, and head ring together; and an outwardly spherically curved head-plate of relatively thin metal, said head-plate having a thinness relative to its diameter such that it deforms under the action of pressures normally maintained within the tank when in use, said head-plate being substantially less than a hemisphere and connected to said door ring at a point intermediate between the cross sectional center of gravity of said ring and an outward extremity of said ring, so that any tendency of the door ring to tilt due to the action upon it of the spherical head-plate when under pressure is minimized and leakage at the gasket is thereby prevented. 25 30 35

5. Apparatus of the character claimed in claim 4, wherein the means for drawing said rings and gasket together are radial lug members adapted to receive bolts.

ROBERT A. DAVIS.
JOHN F. MUMMERT.
